US00D950716S

(12) United States Design Patent (10) Patent No.: US D950,716 S
(45) Date of Patent: * May 3, 2022

(54) MALE URINAL

(71) Applicant: Tilen Tercelj Schweizer, Ljubljana (SI)

(72) Inventor: Tilen Tercelj Schweizer, Ljubljana (SI)

() Term: 15 Years

(21) Appl. No.: 29/724,323

(22) Filed: Feb. 14, 2020

(51) LOC (13) Cl. 24-04

(52) U.S. Cl.

USPC D24/122

(58) Field of Classification Search

USPC D24/117, 121, 122, 123, 127, 128, 224;
D7/691, 700; D23/200, 302, 303, 309,
D23/295; 600/573, 574; 604/329, 322,
604/317, 318, 334; 141/372; 4/144.1,
4/144.2, 144.3, 144.4, 445, 459, 460

CPC A61G 9/00; A61G 9/006

(57) CLAIM

The ornamental design for a male urinal, as shown and described.

DESCRIPTION

FIG. 1 is a perspective view showing my new design;

FIG. 2 is a front view thereof;

FIG. 3 is a back view thereof;

FIG. 4 is a top view thereof;

FIG. 5 is a bottom view thereof;

FIG. 6 is a left side view thereof; and,

FIG. 7 is a right side view thereof.

1 Claim, 7 Drawing Sheets
